UNITED STATES PATENT OFFICE.

HANS BRUNNER, OF AMSTERDAM, NETHERLANDS.

LOCKING DEVICE.

1,413,572.

Specification of Letters Patent. Patented Apr. 25, 1922.

Application filed August 17, 1920. Serial No. 404,061.

To all whom it may concern:

Be it known that I, HANS BRUNNER, citizen of Switzerland, residing at Amsterdam, Netherlands, have invented certain new and useful Improvements in Locking Devices, of which the following is a specification.

This invention relates to a locking device for railway freight cars and has for its object to provide improved means for preventing the opening of locked cars by thieves and like persons without attracting the attention of other people.

The main disadvantage of the locking devices hitherto used and designed, are, that the opening of the lock can be done almost noiselessly.

With the above object in view the invention consists in the details of construction and in the arrangement and combination of parts as will be hereinafter fully described and pointed out in the appended claims, and which allow the opening of the lock only by striking some parts of the lock with a hammer or like heavy tool sufficiently hard to attract the attention.

An embodiment of the present invention is illustrated in the accompanying drawing, in which:

Fig. 1 is a front view;

Fig. 2 is a top view, and

Fig. 3 is a side elevation of the locking device, its casing being omitted.

Referring more particularly to the drawing, 1 indicates an elastic steel plate, adapted to be bent only by striking it hard with a hammer, 2 is a striking pin, which is pressed by means of a spring 3 against the back part of the steel plate 1 and 4 is a cam attached to the striking-pin 2, 5 is a roller supported in one of the legs of an angle lever 6, said roller being pressed against the striking pin 2 by means of a spring 7 working on the other leg of the angle lever 6, and fixed between the guide blocks 8 for guiding said other leg; its end being adapted to engage in the teeth of a pinion 9 mounted on a spindle 10. 11 is an eccentric keyed to said spindle 10 and 12 a locking bolt guided by guides 13, suitably connected to said eccentric 11, and adapted to be moved by turning the spindle

10. A slot 14 for engaging the end of the locking bolt 12 is provided in a locking plate 15, which is guided by means of pins and slots 16 and carries at one of its ends a locking bolt 17, which is adapted to engage in a slot of a brace 18, fastened to one of the door

halves, or if there is only one door it may be fastened to the car body. The locking plate 15 carries a grip or handle 20, by which the plate 15 may be moved up and down, when the plate 15 and the locking bolt 12 are disengaged.

The locking bolt 12 has a stud 21, which rests against the slightly bowed end of the leg 22 of an angle lever, which is turnable around a spindle 23. The other leg of said angle lever carries a grip or handle 24, for operating said lever, which may be provided with the usual means for sealing (not shown on the drawing).

Now the operation of closing and opening the lock will be as follows:

When closing the lock, the projection 17 of the locking plate 15 is put in the slot of the brace 18. Now by striking the elastic steel plate 1 hard with a hammer, the blow will be transmitted to the striking pin 2, which causes said pin at each blow of the hammer to make a down and up motion; the latter on account of the action of the spring 3.

During the downward motion the cam 4 will run against the roller 5, which causes the engagement of the end of the angle lever 6 with the teeth of the pinion 9; by the upward motion however the angle lever and the pinion are disengaged, as the spring 7 pushes the angle lever back in its former position. Every blow on the steel plate 1 causes also a corresponding turning of the pinion 9 and at the same time of the eccentric 11, which leads to an engagement of the locking bolt 12 with the slot 14 of the locking plate 15, and causes also a closing of the locking device.

The locking of the bolt 12 may also be obtained by moving the handle 24 downwards, which causes the angle lever and its leg 22 to turn or swing around the spindle 23, which results in pushing the locking bolt 12 into slot 14.

However this operation is only possible, when the eccentric is not standing in its dead-centre position. If this is the case one or more blows with the hammer will suffice to bring the eccentric 11 into its proper position.

It will be obvious that the position of the angle lever will indicate whether the lock is closed or not.

The opening of the lock can only be obtained by moving the locking bolt in a direction opposite to its closing movement, which

may be achieved by a further turning of the pinion 9 in the same direction by another series of hammer blows on the plate 1, which brings the eccentric 11 over its dead-centre position and moves the bolt 12 out of engagement with the locking plate 15.

The projection 17 of the plate 15 and the brace 18 may then be disengaged by lifting the plate 15 by means of the handle 20, 10 whereafter the car door can be opened.

The opening of the lock from the inside of the car is only possible by removing the casing of the lock (not shown on the drawing) and by moving the locking bolt by 15 hand or by turning the spindle 10 by means of a suitable handle, (not shown on the drawing).

It will be obvious, that there are many other ways, than the one shown on the drawing, for transmitting the motion of the striking pin 2 to the locking bolt 12 without interfering in the least with the idea of this invention.

Having now particularly described and 25 ascertained the nature of my said invention and in what manner the same is to be performed I declare that what I claim is:

1. In a locking device the combination of a locking-plate, a locking bolt, said locking 30 plate adapted to be locked or released by said locking bolt, a flexible elastic steel plate, and means arranged between said steel plate and locking bolt to bring the locking bolt into either its locking or its releasing position by subjecting the steel plate to a series of successive flexures.

2. In a locking device the combination of a locking-plate, a locking bolt, said locking 40 plate adapted to be locked or released by said locking bolt, a flexible elastic steel plate, a spindle arranged between said steel plate and locking bolt, means to rotate said spindle by subjecting the steel plate to a series of successive flexures, and means between 45 said spindle and locking bolt to bring said bolt into either its locking or its releasing position by rotating said spindle.

3. In a locking device the combination of a locking plate, a locking bolt, said locking 50 plate adapted to be locked or released by said locking bolt, a flexible elastic steel plate, a spindle arranged between said steel plate and locking bolt, a striking pin resting against said steel plate and adapted to oscillate up and down when the steel plate is subjected to a series of successive flexures, means for transforming the upward movement of said striking pin into a rotating motion of said spindle, and means between said 55 spindle and locking bolt to bring the locking

bolt into either its locking or its releasing position by the rotation of said spindle.

4. In a lock, the combination of an impact device adapted to be struck by a hammer; a bolt; and mechanical connections between 65 the bolt and the impact device for operating the former consequent upon the striking of the latter.

5. In a lock, the combination of an impact device comprising an oscillatory element; a bolt; and means for imparting a progressive step-by-step movement to the bolt consequent upon the oscillation of said element.

6. In a lock, the combination of an oscillatory element; a ratchet; means for imparting a step-by-step rotary movement to said ratchet consequent upon the oscillation of said element; a bolt; and connections between the bolt and the ratchet for operating 75 the former from the latter.

7. In a lock, the combination of an oscillatory element; a ratchet; means for imparting a step-by-step rotary movement to said ratchet consequent upon the oscillation of 85 said element; an eccentric connected to rotate with the ratchet; a bolt; and operating connections between said eccentric and said bolt.

8. In a lock, the combination of an impact device comprising a flexible element adapted to be repeatedly struck by a hammer, and an element adapted to oscillate consequent upon the flexure of the first-named element; a bolt; and mechanical connections between said bolt and the second-named element for operating the former 90 consequent upon the oscillation of the latter.

9. In a lock, the combination of an element adapted to be repeatedly oscillated; 100 a cam thereon; a bolt; and means operated by said cam during the successive oscillations of said element for progressively advancing said bolt into locking position.

10. In a lock, the combination of an oscillatory element; a cam thereon; a bolt; a ratchet; means operated by said cam during the oscillation of said element for driving 105 said ratchet; and means operated by said ratchet for advancing said bolt into locking 110 position.

11. In a lock, the combination of an oscillatory striker pin; a bolt; and connections between said pin and said bolt for advancing 115 the latter into locking position during and consequent upon the oscillation of the former.

In testimony whereof he affixes his signature.

HANS BRUNNER.
